PRESSER FOOT FOR SEWING MACHINES

Hans Hacklander, Tinley Park, and Harold J. Le Vesconte, Western Springs, Ill., assignors to Union Special Machine Company, Chicago, Ill., a corporation of Illinois

Application September 19, 1936, Serial No. 102,400

20 Claims. (Cl. 112—235)

This invention relates to presser feet for sewing machines; and it has more particular reference to presser feet useful in connection with sewing machines of the type featured in a co-pending application Serial No. 101,588, filed by us concurrently herewith, and designed to form covered seams after the method disclosed in another co-pending application Serial No. 1,885 filed by Norman V. Christensen on January 15, 1935. In 10 the referred to method, the fabric is arranged with edge margins thereof placed in upstanding abutted relation, the edges trimmed, the abutted margins turned laterally into superimposed relation flat upon the fabric, and said margins finally 15 united by a central line of stitches passing through all three fabric thicknesses at the fold, and parallel outer lines of stitching through the fabric at opposite sides of the fold, with crosswise loops overlying the fold and connecting the outer stitch 20 lines.

The aim of our invention is to provide a simple and reliable presser foot with means capable, as the fabric is advanced in the machine, of trimming the abutted edges and folding over the edges laterally as aforesaid, and of holding the fold down for presentation to the stitching instrumentalities of the machine.

In connection with a presser foot having the above attributes, it is a further object of our invention to provide improved means which will compensate for variations in the thickness of the fabric at opposite sides of the fold, and which will progressively yield to facilitate passage of cross seams and other irregularities in the fabric beneath the presser foot.

Other objects and attendant advantages will appear from the detailed description which follows of the attached drawings, wherein

Fig. I is a fragmentary view, partly in front elevation and partly in longitudinal section, of a sewing machine like that of the application supra embodying our improved presser foot.

Fig. II is a view looking as indicated by the arrows II—II in Fig. I.

Fig. III is a plan sectional view taken as indicated by the arrows III—III in Fig. I.

Fig. IV is an inverted plan view looking as indicated by the arrows IV—IV in Fig. I.

Fig. V is a fragmentary top plan view of the presser foot with certain of its appendages removed.

Fig. VI is an exploded view in perspective, showing the presser foot and various parts associated therewith.

Fig. VII is a fragmentary elevation of the presser foot corresponding to Fig. I.

Figs. VIII, IX and X are views like Fig. VII showing the action of the presser foot incident to passage therebeneath of a cross seam in the 5 fabric.

Fig. XI is a cross sectional view taken as indicated by the arrows XI—XI in Fig. V.

Fig. XII is a view corresponding to Fig. XI showing the fabric after the trimming of its up-standing abutting edges.

Figs. XIII and XIV are cross sectional views of the presser foot taken as indicated respectively by the arrows XIII—XIII and XIV—XIV in Fig. V.

Fig. XV is a view like Fig. XIII showing the action of the presser foot incident to passage therebeneath of different fabric thicknesses at opposite sides of the abutted margins.

Fig. XVI is a plan view of a supplemental presser plate forming part of the presser foot, together 20 with the seaming needles.

Figs. XVII and XVIII are cross sections through the same formed with the needles arranged as in Fig. XVI.

Figs. XIX, XX and XXI are views corresponding to Figs. XVI, XVII and XVIII showing an alternative arrangement of the needles, and the seam resulting therefrom; and

Figs. XXII and XXIII are views corresponding to Figs. XVI and XVIII showing another alternative arrangement of the needles and the resulting seam.

With more specific reference to these illustrations, the numeral 1 comprehensively designates the presser foot of our invention, the same being 35 longitudinally divided, with provision, between flat sole portions 2 and 3, of a slot 4 for passage of the abutted upstanding margins M, M' of fabric F (Figs. III and XI—XIII) progressed forwardly along the work arm 5 of the machine by the feed 40 dogs indicated at 6 and 7 in Fig. I.

Fulcrumed to swing about a transverse pin 12 within the hollow of the work supporting arm 5 at the front end of the latter, is an arm 13 which carries a group of laterally-spaced seaming needles including a center needle 14 and a pair of transversely aligned flanking outer needles 15, 16. In Figs. I, III—V and XVI, the flanking needles 15 and 16 are placed ahead of the center needle 14 in the direction of feeding, which, in this instance, is outward of the arm 5 as indicated by an arrow in Fig. I. The needle carrying arm 13 is adapted to be oscillated about its fulcrum 12 by a reciprocated horizontal link 17 so that the needles 14—16 pass through the fabric from be- 55

neath. Cooperating respectively with the needles 14 and 15, 16 above the fabric, are loopers 18, 19 which are carried by an arm 20 suitably actuated to effect the required loop taking and needle avoiding movements of said loopers. At its heel end, the presser foot 1 has an arched shank 21 which is secured by a screw 22 to the lower end of the vertical presser bar 23 of the machine, said bar having sliding guidance in a sleeve 25 journaled for oscillation in the bottom of a fixed head 26 of the machine frame which overhangs the front end of the work supporting arm 5. By a suitable relatively heavy spring, not shown, the presser bar 23 is yieldingly urged downward to maintain the presser foot 1 in contact with the fabric on the work arm 5, and is restrained against rotation by coaction of a clevised lateral projection 27 of the shank 21 with a guide stud 28 pendant from the head 26.

In order that variations in the thickness of fabric advanced beneath the presser foot may be automatically compensated for, the sole portions 2, 3 of the latter are fitted with conformative shoes 29 and 30 fashioned from flexible sheet metal, 25 having flat bottoms and upwardly turned toe ends rounded as at 31, 32 to conform with the upwardly curved toe ends of said sole portions and formed with inward lap projections 33, 34. From Figs. III, IV and VI it will be observed that the 30 projections 33, 34 have longitudinal notches 35, 36 which engage with studs 37, 38 upstanding from the toe ends of the sole portions 2 and 3. The upwardly turned heel ends 39, 40 of the shoes are formed with inwardly directed lugs 41, 42 which loosely 35 engage recesses 43, 44 in the tops of the sole portions 2 and 3 at the heel ends of the latter, see Figs. III, V and VI. At intervals along their 40 lengths, the flat bottoms of the shoes 29 and 30 are respectively formed with pressed-out longitudinal spring tongues 45 and 46 which reach upward and engage the shoulders of transverse recesses 47 and 48 in the bottoms of the sole portions 2 and 3. When fully compressed as in Fig. I, the spring tongues 45, 46 are wholly accommodated within the recesses 47, 48 with the flat bottoms of the shoes 29, 30 contacting with the bottoms of the soles 2 and 3. The inner edge of the toe end of the portion 3 of the presser foot is beveled as at 49, the angle of the bevel gradually 45 approaching the horizontal and said bevel flaring in the direction of feed as at 49a and terminating in a point 50. With the bevel 49 cooperates a folding member 51 having the form of a bar with a bevel 52 complementary to the bevel 49, and a 50 lateral shank 53 slidingly engaging in a transverse guideway 54 of the portion 2 of the presser foot. A leaf spring 55 urges the folding member inward yieldingly to turn over the upstanding abutted margins M, M' of the fabric F laterally as 55 shown in Figs. XI, XII and XIII flat in superimposition upon said fabric. During advance of the fabric beneath the presser foot 1, its upstanding edge margins M, M' are trimmed to an even height by a pair of cooperating trimming blades 56, 57. The blade 56 has dovetailed engagement with a transverse slot 58 in the portion 3 of the presser foot in line with the shank 53 of the folding element 51, and is secured in position by a clamp plate 59 having an angular cut at 60 to deflect the 60 trimmings laterally of the direction of feed. The trimming blade 57 is adjustably set in the down-turned end of an arm 61 which is clamped to the oscillating sleeve 25 hereinbefore referred to. The blade 57 is flexible and curved concentrically 75 with the axis of the sleeve 25 as shown in Fig. III,

and has a forward projection 62 which bears upon the top face of the fixed blade 56. As a consequence, the cutting edges 63 and 64 of the trimming blades 56 and 57 are maintained in exact cutting alignment vertically. Through oscillation of the sleeve 25 induced by suitable means not shown, the blade 57 is swung back and forth crosswise of the line of feed, and, by cooperation with the fixed blade 56 progressively trims the upturned edges M, M' of the fabric F in a manner which will be readily apparent from Fig. III. As shown in Fig. II, the cutting edge 63 of the fixed blade 56 slightly overhangs the slot 4 through the presser foot. The aft end of the slot 4 is occupied by a supplemental presser plate 65 which is provided with an aperture 66 for passage of the needles 14-16 and which has a cross pin 67 medially attached thereto with its ends engaging vertically open bearing notches 68 and 69 in the tops of the sole portions 2 and 3 of the presser foot. A double finger spring 70 secured by a screw 71 within the arch of the presser foot shank 21 has its ends curved to engage over the cross pin 67. As a result of this arrangement, the supplemental presser plate 65 is afforded the capacity to move up and down as well as to pivot in respect to the presser foot. The function of the supplemental presser plate 65 is to hold down the fabric margins M, M' after they have been trimmed and turned over for presentation to the needles 14-16 as shown in Fig. XIV, with the fold N guided by a recess 72 in the bottom of said plate. The aperture 66 in the supplemental presser plate 65 will be noted from Figs. III-VI and XVI has forwardly open longitudinal notches 35 74, 75 and 76 in the line of the needles 14, 15 and 16 with provision of a central tongue 77 over which the looper loops are laid, said tongue being rounded downwardly at its end to facilitate the release of said loops as the fabric advances.

When the fabric along the opposing edge margins is of the same thickness, the resistance of the spring tongues 45, 46 of both shoes 29 and 30 will be overcome by the heavier spring acting on the presser bar 23, with the result that the sole portions 2 and 3 of the presser foot bear full upon the flat portions of said shoes with the latter bearing in turn upon the fabric as in Figs. XI-XIII. If, on the other hand, the fabric is thicker along one edge or reinforced by an additional fabric layer as exemplified at F' in Fig. XV, the presser foot will be correspondingly lifted bodily, and the shoe 30 independently forced downward by its spring tongues 46 away from the sole portions 2 and 3, to hold down the single thickness fabric along the opposite edge. During passage of cross seams or other irregularities in the fabric, the shoes 29 and 30 function as shown in Figs. VIII-X, that is to say, they yield to sinuous upward deflection as the cross seam or other irregularity travels beneath them. Such action of the shoes 29 and 30 is possible by virtue of the fact that they fit loosely over the sole portions 2 and 3 of the presser foot and are therefore able to move up and down under the influence of their spring tongues 45 and 46 and to expand or contract lengthwise slightly as required, their detachment from the foot being prevented through coaction of the longitudinal notches 35, 36 at their toe ends with the retaining studs 37, 38, and through coaction of the lugs 41, 42 at their heel ends within the keeper recesses 43 and 44 of said presser foot.

With the needles arranged as in Figs. III, IV and XVI, the crosswise connecting loop L' of a

pair of outer needle loops, S^1 and S^2 formed during one stitching cycle as in Fig. XVII, is overlapped by the looper loop L of the center needle loop S during the succeeding stitching cycle as in Fig. XVIII.

5. By placing the central needle 14 in advance of the outer or flanking needles 15 and 16 after the manner of Fig. XIX, the loop L of a central needle loop S , formed as in Fig. XX during one stitching 10 cycle, is covered by the crosswise looper loop L' of a pair of outer needle loops S^1 , S^2 formed during the succeeding stitching cycle as in Fig. XXI. For the last described arrangement of the needles, the supplemental presser plate 65 (Fig. XIX) is 15 provided with a separate aperture $66a$ for passage of the central needle 14 .

By arranging all three needles 14 , 15 and 16 abreast as in Fig. XXII and employing a single looper to cooperate with them, the needle loops S , S^1 and S^2 are concurrently connected crosswise 20 during each stitching cycle after the manner shown in Fig. XXIII. The supplemental presser plate 65 of Fig. XXII is like that of Fig. XVI except for lengthening of the notch 14 for the central needle 14 .

In all cases, it will be noted that the central needle loops S pass through the fabric F as well as the two superimposed margins M , M' at the fold N , and that the fold is covered by crosswise 30 looper loops L' connecting the outer needle loops S^1 , S^2 which pass through the fabric immediately beyond the fold.

While we have herein disclosed our invention in a form which gives very satisfactory service, 35 various modifications as to details can of course be made within the scope of the appended claims. For example, instead of being integral with the shoes 29 and 30 as hereinbefore described, the spring tongues 45 and 46 may be separately made 40 and attached; or again; coiled springs may be substituted and accommodated within suitable recesses in the bottoms of the sole portions 2 and 3 of the presser foot.

Having thus described our invention, we claim: 45

1. A presser foot for sewing machines embodying means for laterally folding over upstanding abutted margins of juxtaposed advancing fabric portions both in the same direction flat into superimposition upon each other and upon one of the fabric portions; and independently yielding means centrally of the presser foot to hold down the fold for stitching.

2. A presser foot for sewing machines embodying means for laterally folding over upstanding abutting margins of juxtaposed advancing fabric portions both in the same direction flat into superimposition upon each other and upon one of the fabric portions; means for trimming the edges of said margins before folding, and independently 50 yielding means centrally of the presser foot to hold down the fold for stitching.

3. A presser foot for sewing machines having a longitudinal slot open at the toe end to receive a longitudinally slot open at the toe end to receive upstanding abutted margins of advancing fabric; 55 a laterally yielding member with an inclined surface progressively-decreasing in angularity toward the horizontal and cooperating with a complementally-configured surface along one edge of the slot to fold over the abutted margins flat into superimposition upon the fabric; and independently yielding means to hold down the fold for stitching.

4. A presser foot for sewing machines having a longitudinal slot open at the toe end to receive 60 upstanding abutted margins of advancing fabric;

a member in the form of a bar with an inclined surface progressively increasing in angularity toward the horizontal to cooperate with a complementally-configured surface along one edge of the slot in folding over the abutted margins flat 5 into superimposition upon fabric, said member having a lateral shank slidably guided in one side of the presser foot; a spring bearing against the end of said shank to yieldingly urge the folding member inward; and independently yielding 10 means to hold down the fold for stitching.

5. A presser foot for sewing machines having a longitudinal slot open at the toe end to receive upstanding abutted margins of juxtaposed advancing fabric portions; means for laterally folding over the margins both in the same direction flat into superimposition upon each other and upon one of the fabric portions incident to advance in the slot; and independently yielding means centrally of the presser foot to hold down 20 the fold for stitching.

6. A presser foot for sewing machines embodying means for laterally folding over upstanding abutted margins of juxtaposed advancing fabric portions both in the same direction flat into superimposition upon each other and upon one of the fabric portions; and an independently-yielding supplemental presser plate centrally of the presser foot to hold down the fold for stitching, said plate having an opening for a stitching needle 30 adapted to pass through all three fabric thicknesses of the fold.

7. A presser foot for sewing machines embodying means for laterally folding over upstanding abutted margins of juxtaposed advancing fabric 35 portions both in the same direction flat into superimposition upon each other and upon one of the fabric portions; and an independently yielding supplemental presser plate centrally of the presser foot to hold down the fold for stitching, said plate having an aperture for a group of laterally-spaced needles including a central needle to pass through all three fabric thicknesses at the fold, and a pair of outer needles to pass through the fabric respectively at opposite sides 40 of the fold.

8. A presser foot for sewing machines embodying means for laterally folding over upstanding abutted margins of advancing fabric flat into superimposition upon the fabric; and an independently yielding supplemental presser plate to hold down the fold for stitching, said plate having an aperture with longitudinal notches open forwardly in the direction of feed respectively for a central needle to pass through all three fabric 50 thicknesses at the fold, and a pair of outer needles offset in the line of feed to penetrate the fabric respectively at opposite sides of the fold.

9. A presser foot for sewing machines embodying means for laterally folding over upstanding abutted margins of advancing fabric flat into superimposition upon the fabric; and an independently yielding supplemental presser plate to hold down the fold for stitching, said plate having an aperture with longitudinal notches forwardly open in the direction of feed for a group of transversely aligned needles, including a central needle to penetrate all three fabric thicknesses at the fold, and a pair of outer needles to penetrate the fabric at opposite sides of the fold. 65

10. A presser foot for sewing machines embodying means for laterally folding over upstanding abutted margins of juxtaposed advancing fabric portions both in the same direction flat into superimposition upon one of the fabric portions; 75

and an independently yielding supplemental presser plate to hold down the fold for stitching, said plate having capacity for vertical as well as pivotal movement to facilitate passage thereunder of cross seams in the fabric.

5. A presser foot for sewing machines comprising a sole portion; and an associated fabric-engaging shoe capable of independent vertical movement bodily, said shoe having its opposite ends loosely engaging over the corresponding ends of the presser foot; and spring means integrally-formed with the shoe and tending to urge it downward of the presser foot.

11. A presser foot for sewing machines comprising a sole portion; and an associated fabric-engaging shoe capable of independent vertical movement bodily, said shoe being fashioned from flexible sheet metal with its opposite ends turned upward and toward each other to loosely engage over the ends of the presser foot, and having upwardly punched-out spring tongues at intervals longitudinally thereof to react against the bottom of the sole portion.

12. A presser foot for sewing machines comprising a sole portion; and an associated fabric-engaging shoe capable of independent vertical movement bodily, said shoe being fashioned from flexible metal with its opposite ends turned upward and toward each other to loosely engage over the ends of the presser foot, and having upwardly punched-out spring tongues at intervals longitudinally thereof engaging shoulders of transverse receiving recesses in the bottom of the sole portion.

13. A presser foot for sewing machines comprising a sole portion; and an associated fabric-engaging shoe capable of independent vertical movement bodily, said shoe being fashioned from flexible metal with its opposite ends turned upward and toward each other to loosely engage over the ends of the presser foot, and having upwardly punched-out spring tongues at intervals longitudinally thereof engaging shoulders of transverse receiving recesses in the bottom of the sole portion.

14. A presser foot for sewing machines comprising a sole portion; an associated fabric-engaging shoe capable of independent vertical movement bodily with its ends turned upward and toward each other to engage loosely over

40 the ends of the presser foot, the inwardly-turned portion at the toe end of the shoe being longitudinally notched to engage a retaining stud up-

standing from the toe end of the presser foot, and the inwardly turned portion at the heel end

45 engaging a retaining notch at the top of the presser foot heel; and spring means tending to urge the shoe downward of the presser foot.

15. A presser foot for sewing machines comprising a sole portion; and an associated shoe capable of independent vertical movement bodily, said shoe being fashioned from flexible metal with its ends turned upward and toward each other to engage loosely over the ends of the presser foot, the inwardly-directed terminal portion at the toe end of the shoe having a longitudinal notch engaging a retaining stud upstanding from the toe end of the presser foot, and the inwardly-turned terminal portion at the heel end engaging a retaining notch in the top of the presser foot heel, and said shoe formed with punched out upward spring tongues at intervals longitudinally thereof to react against the bottom of the presser foot.

16. A presser foot for sewing machines comprising sole portions at opposite sides of a longitudinal slot to receive upstanding abutted margins of advancing fabric; and respectively associated shoes capable of independent vertical movement bodily and having their ends loosely engaging over the corresponding ends of the soles of the presser foot; and spring means tending to urge the shoes downward of said sole portions.

17. A presser foot for sewing machines comprising sole portions at opposite sides of a longitudinal slot to receive upstanding abutted margins of advancing fabric; and respectively associated fabric-engaging shoes capable of independent vertical movement bodily, said shoes being fashioned from flexible metal with their ends turned upward and toward each other to loosely engage over the corresponding ends of the sole portions of the presser foot, and having spring 10 tongues upwardly offset at intervals lengthwise thereof to react against the bottoms of said sole portions.

18. A presser foot for sewing machines comprising sole portions at opposite sides of a longitudinal slot to receive upstanding abutted margins of advancing fabric; respectively associated fabric-engaging shoes capable of independent vertical movement bodily, said shoes being fashioned from flexible metal with their ends turned upward and toward each other to engage loosely over the corresponding ends of the presser foot, the inwardly-turned terminal portions at the toe ends of said shoes being longitudinally notched to engage retaining studs upstanding from the tops of the shoes of the sole portions, and the inwardly-turned terminal portions at the heel ends engaging retaining recesses in the tops of the heel of the sole portions; and spring means tending to urge the shoes downward of said sole portions.

19. A presser foot for sewing machines comprising sole portions at opposite sides of a longitudinal slot to receive upstanding abutted margins of advancing fabric; and respectively associated fabric-engaging shoes capable of independent vertical movement bodily, said shoes being fashioned from flexible metal with their ends turned upward and inward toward each other to engage loosely over the corresponding 40 ends of the presser foot, the inward terminal portions at the toe ends of said shoes being longitudinally notched to engage retaining studs upstanding from the tops of the shoes of the sole portions, and the inward terminal portions at the heel ends engaging retaining recesses in the tops of the heels of the sole portions, and said shoes having upwardly punched-out spring tongues at intervals longitudinally thereof to react against the bottoms of said sole portions.

20. A presser foot for sewing machines comprising sole portions at opposite sides of a longitudinal slot to receive upstanding abutted margins of advancing fabric; and respectively associated fabric-engaging shoes capable of independent vertical movement bodily, said shoes being fashioned from flexible metal with their ends turned upward and toward each other to engage loosely over the corresponding ends of the presser foot, the inward terminal portions at the toe ends 60 of said shoes being longitudinally notched to engage retaining studs upstanding from the tops of the toes of the sole portions, and the inwardly turned terminal portions at the heel ends engaging retaining recesses in the tops of the heels of the sole portions, and said shoes having upwardly punched-out spring tongues at intervals longitudinally thereof with their ends engaging the shoulders of transverse recesses in the bottoms of said sole portions.

HANS HACKLANDER.

HAROLD J. LE VESCONTE.
